ABSTRACT

An improved crutch quickly and conveniently convertible for use on normally dry or on slippery surfaces wherein a retractable prong or spike is incorporated in the base of the crutch; the spike being lowered or withdrawn by means of a hand operated mechanism located at or immediately below the hand grip of the crutch.

FIG. 7

CONVERTIBLE CRUTCH

BACKGROUND OF THE INVENTION

Many who have had to walk with the aid of a pair of crutches have undoubtedly experienced the difficulty and danger involved in trying to find a reliable footing for the base of a crutch on slippery or icy sidewalks or pavements. The ordinary crutch is almost useless in such a situation and the hazard of adding further injury to the initial infirmity is always a possibility.

The development of a fixed tread for the base of a crutch which will serve equally well for normal and for icy surfaces must rely on a compromise between a spike which is ideal for an icy surface but too harsh and abrasive for normal surfaces and a rubber tread which is ideal for normal surfaces but lacks the ability to grip an icy surface.

An alternate is a special crutch which is easily and quickly convertible from an ideal crutch for ice to an ideal crutch for normal surfaces.

An improved crutch of this type is urgently needed as a humanitarian aid to a significant segment of our population which has already suffered misfortune and can ill afford further injury.

SUMMARY OF THE INVENTION

In accordance with the invention claimed, an improved crutch is provided which incorporates a retractable spike or prong which is useful for walking on icy surfaces.

It is, therefore, one object of this invention to provide a crutch which is ideally suited for use on icy surfaces.

Another object of this invention is to provide such a crutch with a means for retracting the prong or spike thereby converting the crutch into an ideal appliance for use on normal surfaces.

A further object of this invention is to provide such a crutch wherein the retracting means may be easily and quickly operated by the user while standing or pausing between slippery and normal surfaces.

A still further object of this invention is to provide such a crutch which is light in weight, easy to handle, and is of substantially the same size as an ordinary crutch.

A still further object of this invention is to provide such a crutch in a simple and inexpensive design which is at the same time durable and attractive.

Further objects and advantages of the invention will become apparent as the following description proceeds and the features of novelty which characterize this invention will be pointed out with particularity in the claims annexed to and forming a part of this specification.

BRIEF DESCRIPTION OF THE DRAWING

The present invention may be more readily described by reference to the accompanying drawing in which:

FIG. 1 is a perspective view of a convertible crutch embodying the invention.

FIG. 2 is a partial cross-sectional view of the crutch shown in FIG. 1 taken along line 2—2.

FIG. 3 is a cross-sectional view of the rubber tread of the crutch shown in FIG. 1 taken along line 3—3.

FIG. 4 is an enlarged partial-side view of the retracting mechanism of the crutch shown in FIG. 1 with the mechanism shifted to a different state.

FIG. 5 is an exploded assembly view of the retracting mechanism employed in the crutch shown in FIGS. 1—4.

FIG. 6 is an illustration of an alternate means for retracting the spike showing a second embodiment of the invention.

FIG. 7 is a further illustration of the retracting mechanism shown in FIG. 6 in a different state.

FIG. 8 is an enlarged partial side view of the retracting means shown in FIGS. 6 and 7 taken along the line 8—8 of FIG. 7.

FIG. 9 is an exploded assembly view of the retracting mechanism shown in FIGS. 6, 7 and 8.

DESCRIPTION OF THE PREFERRED EMBODIMENT

Referring more particularly to the drawing by characters of reference, FIGS. 1—5 disclose a crutch 10 comprising a pair of spaced elongated support members 11 and 12 interconnected at one end by a padded cross member 13 which fits under the armpits of the user, a handgrip 14 arranged laterally between and attached to the support member 11 and 12 at a point between their ends, and a tread member 15 interconnecting support members 11 and 12 at the base of the crutch. In accordance with the invention claimed a pointed spike 16 is arranged to pass through an opening 17 in tread member 15 and is secured to a rod 18 arranged to extend between support members 11 and 12 substantially in the same plane. A retractor support member 19, retractor mechanism 20, and a coupler 21 interconnecting rod 18 to the retractor mechanism 20 is provided for controlling the position of the spike. Spike 16 may be the pointed end of rod 18 or a separate member secured or threaded thereto.

The retractor mechanism 20 comprises a flat rectangular plate or block 22 supporting a staple or u-shaped bar 23 within a pair of apertures later discussed. Block 22 is pivotally mounted by means of a centrally located pivot pin 24, a compression spring 25 and a washer 26 to support member 19 directly over a cross-shaped depression 27 in support member 19. The cross-shaped depression 27 in support member 19 is suitably proportioned and dimensioned to receive and contain block 22 within either of its perpendicularly related arms.

U-shaped bar 23 is fixedly attached at the ends of its legs 23A and 23B in aligned holes 35A and 35B in block 22 and perpendicularly secured thereto by means of screws 28A and 28B as shown.

The mounting of block 22 to support member 19 entails the insertion of pivot pin 24 through washer 26, spring 25, center hole 29 of block 22 and center hole 31 in depression 27 formed in member 19. Pivot pin 24 is then secured to support member 19 by means of a screw or spreading rivet 32 applied from the opposite side of support member 19 within which depression 27 is formed.

Block 22 may be aligned within either of the two perpendicular arms of depression 27 by the user grabbing a hold of the u-shaped bar 23 and pulling it away from the support member 19 against the bias of spring 25 and then upon being released after proper rotation and relative positioning it will fall into one of the arms of depression 27 through the action of spring 25.

Coupler 21 has a generally cylindrical shape modified at one end by the removal of a semi-cylindrical section to provide a flat surface 33. Surface 33 passes lon-

itudinally through the approximate center of the cylindrical outline of coupler 21. A hole 34 perpendicularly arranged to pass through surface 33 at one end of the coupler 11 is dimensioned to receive leg 23B of u-shaped bar 23 in a pivotal relationship.

In the assembly of u-shaped bar 23 to block 22 its leg 23B is first passed through hole 34 of coupler 21. Legs 23A and 23B of the u-shaped bar are then passed, respectively, through holes 35A and 35B in block 22, holes 35A and 35B being aligned along a longitudinal centerline of block 22. The surface 33 of coupler 21 now rests adjacent the surface of block 22 and is retained in that position by an annular shoulder on leg 23B adjacent the opposite end of hole 34.

Rod 18 supporting spike 16 at its lower end is attached at its upper end within an aperture arranged along the longitudinal axis of coupler 21 for receiving and retaining rod 18. Spike 16 is attached by means of threads 36 to the lower end of rod 18, the length of rod 18 being appropriately dimensioned to allow spike 16 to penetrate center hole 17 in tread 15 at the base of crutch 10.

As shown in FIG. 1, when block 22 is vertically oriented and rests in the vertical arm of depression 27 of support member 19, leg 23B of bar 23 is in its lowermost position and hence spike 16 coupled to leg 23B is consequently in its lowermost position. In this position tip 36 of spike 16 is exposed below the bottom surface 37 of tread 15. By virtue of the action of spring 25 in forcing block 22 to remain rigidly secured within the vertical arms of depression 27, spike 16 is rigidly held in this extended position wherein it serves reliably as a skid-proof tread at the base of crutch 20 for use in preventing slippage of crutch 20 on icy or slippery surfaces.

When the user of the crutch has cleared the slippery areas and wishes to pass over the non-slippery surfaces which might be damaged or marred by spike 16, he merely grasps u-shaped bar 23, pulls it outwardly from the crutch support member 19 to withdraw block 22 from depression 27 formed therein. He then rotates block 22 about pivot pin 24 through an angle of 90 degrees and then releases it to allow spring 25 to move block 22 into the horizontal arm of depression 27, as shown in FIG. 4. Leg 23B of the u-shaped bar 23 is now moved to a relatively higher position carrying coupler 21, rod 18 and spike 16 upward with support member 11 and 12 of the crutch sufficiently to cause spike 16 to be withdrawn inside hole 17 so that tip 36 no longer extends below surface 37 at the base of tread 15. The flexible hard rubber body of tread 15 now serves as an appropriate bearing surface for the crutch.

As shown in FIGS. 1 and 3, tread 15 is formed in a manner which permits its easy replacement if it becomes excessively worn. In addition to its center hole 17 which receives and horizontally positions spike 16, two dead holes 38 and 39 may be provided one on either side of hole 17. These are arranged to receive the bases of vertical support members 11 and 12 of crutch 10. The dimensions of holes 38 and 39 are appropriate to produce a force fit with member 11 and 12.

A second embodiment of the invention as shown in FIGS. 6-9 utilizes a retracting mechanism 41 comprising a modified supporting member 42 and cam-shaped block 43.

Supporting member 42 is fashioned from flat stock which is mounted as a web spanning vertical supports

11 and 12 just below hand grip 14 as did member 19 of the first embodiment. In place of the cross-shaped depression 27 in support member 19 of the first embodiment, supporting member 42 has a depression 44 which is semicircular in shape and opens at its lower edge as shown in FIG. 9.

Cam-shaped block 43 is cut from a piece of flat stock of a thickness nearly equal to the depth of depression 44 in the shape of a circle supplemented by a ninety degree sector of a second, slightly larger circle. The ninety degree sector forms a shoulder or protrusion 45 forming a first radially extending shoulder 45A and a second radially extending shoulder 45B.

Cam-shaped block 43 is pivotally mounted to member 42 by means of a pivot pin 46 passing through a center hole 47 in block 43 and a center hole 48 in supporting member 42. The smaller circle of block 43 fits rotatably inside semi-circular depression 44 of supporting member 42 as shown in FIGS. 6, 7 and 8.

The cam-shaped block 43 is rotatable about pivot pin 46 within depression 44 and when rotated in a counter clockwise direction is stopped when shoulder 45A comes into contact with a bumper surface 49A located on the under side of supporting member 42 just to the right of depression 44. Its clockwise rotation is stopped when its shoulder 45B comes into contact with bumper surface 49B located on the under side of supporting member 42 just to the left of depression 44.

Spike 16 is supported by rod 18 coupled to the shifting mechanism 41 by means of the coupler 21, in the manner described for FIGS. 1-5, with coupler 21 being pivotally attached to the shifting mechanism 41 by pivot pin 51 passing through hole 34 of coupler 21 and hole 52 located near the edge of protrusion 45 and shoulder 45B as shown in FIG. 9.

It will now be observed that by virtue of the location of hole 52 near shoulder 45B rather than at the center of protrusion 45, pivot pin 51 is in a relatively higher position when block 43 is rotated fully clockwise and in a relatively lower position when block 43 is rotated fully counterclockwise when the crutch is in a vertical position relative to the ground. Rod 18 is appropriately dimensioned to provide for the protrusion of spike 16 under the fully counter clockwise condition of FIG. 7 and to provide for retraction of spike 16 under the fully clockwise condition of FIG. 6.

To provide for mechanical stability of block 43 in either the clockwise or counter clockwise positions, a tension spring 53 is attached at one end to a ring 54 extending from the head of pivot pin 51 and at the other end to a ring 55 secured to member 42. The position of ring 55 is chosen to cause the line of force produced by spring 53 to lie above pin 46 when block 43 is rotated clockwise thereby sustaining block 43 in its clockwise position. Similarly, when block 43 is rotated counterclockwise, the line of force of spring 53 lies to the right of pin 46 where it is sustained in that counterclockwise position.

The retracting mechanism may be easily and conveniently shifted from one position to the other to retract or expose spike 16 by appropriately rotating cam-shaped block 43 to either of the two stable conditions against the initially restraining action of spring 53.

An improved crutch has thus been provided which is easily converted in a matter of seconds for use on slippery or on normal dry surfaces. Two novel and practical retracting mechanisms have been provided as

means for exposing or retracting the spike at the base of the crutch. Other variations in design will be obvious such as the incorporation of the retracting mechanism into the hand grip as an integral part thereof.

In accordance with good manufacturing practice, the 5 structural members of the disclosed crutch may be formed of metal, plastic or wood with the tread member formed of a resilient material such as, for example, rubber or suitable plastic either smooth or formed with ridges or other suitable gripping surfaces.

Although but two embodiments of the invention have been illustrated and described, it will be apparent to those skilled in the art that various changes and modifications may be made therein without departing from the spirit of the invention or from the scope of the ap- 15 pended claims.

What is claimed is:

1. A crutch convertible for use on dry or slippery surfaces comprising:
 a pair of spacedly arranged elongated support mem- 20 bers interconnected at one end by a cross member for fitting under the arm pits of a user,
 a handgrip arranged to extend laterally between said support members at a point between their ends,
 a tread member formed of resilient material for grip- 25 ping a smooth surface interconnecting said support members at their other ground engaging ends,
 said tread member having an aperture extending

10

therethrough longitudinally of said crutch,
 a rod arranged between and within the plane of said support members longitudinally of said crutch with one end movable in said aperture of said tread member,
 a spike removably attached to said one end of said rod for aiding in gripping a slippery surface,
 the other end of said rod extending adjacent to said handgrip,
 means mounted adjacent said handgrip and attached to said other end of said rod for moving said rod within said aperture of said tread member to protrude said one end of said rod beyond said tread member or retract it within said aperture,
 said means comprising a locking means for holding said rod in its retracted and extended positions,
 said locking means comprises a supporting plate having a slotted cross like configuration with one arm of the slot extending longitudinally of the crutch and the other arm laterally thereof,
 a flat plate pivotally mounted at said one end of said rod for fitting into either arm of said slotted configuration, and
 means for moving said plate into either arm of said slotted like configuration to lock said rod in either the retracted or protruding position.
